UNITED STATES PATENT OFFICE.

WILLIAM H. LUCAS, OF PHILADELPHIA, PENNSYLVANIA, ASSIGNOR TO FRED F. ESPEN, JACOB ESPEN, JR., AND WILLIAM H. LUCAS, ALL OF PHILADELPHIA, PENNSYLVANIA, A COPARTNERSHIP AS ESPEN-LUCAS MACHINE WORKS.

METAL-CUTTING MACHINE.

1,109,344.

Specification of Letters Patent.

Patented Sept. 1, 1914.

Application filed June 19, 1911. Serial No. 634,096.

To all whom it may concern:

Be it known that I, WILLIAM H. LUCAS, a citizen of the United States, residing in Philadelphia, Pennsylvania, have invented 5 certain improvements in Metal-Cutting Machines, of which the following is a specification.

The object of my invention is to provide for the simultaneous cutting of relatively 10 long bars, beams, rails, or the like (hereinafter, for convenience, referred to as "bars") into shorter pieces either of uniform or of dissimilar lengths.

In the accompanying drawings—Figure 1 15 is an end view of a machine constructed in accordance with my invention; Fig. 2 is a transverse section of the same on the line *a—a*, Fig. 1, and on an enlarged scale, and Fig. 3 is a diagram on a reduced scale, illustrating one method of disposing of the 20 elements of the machine on a common bed or foundation plate for the purpose of cutting the bar into pieces of uniform length.

The machine is of the type known as a 25 "cold saw" cutting machine, and in carrying out my invention I dispose a number of such machines upon a common bed or foundation and drive them all from a common shaft, means being provided for adjusting the machines from and toward each 30 other on the bed to vary the distances between the cuts made by the individual machines, and I have also devised a special form of machine having two saws so 35 mounted upon the same shaft that they will always occupy a position relatively close to the shaft bearing while still permitting of a certain amount of adjustability on the shaft, in order to vary the distances between the saws to accord with the 40 desired distances between the cuts made thereby.

In Fig. 1 of the drawing, 1 represents the bed or foundation which has longitudinal slide-ways 2 for the support of feet 3 upon the frame of each machine, and longitudinal racks 4 for engagement with pinions 5 on the shaft 6, mounted in suitable bearings on the frame of each machine, so 45 that by turning this shaft in one direction or the other the machines may be moved to right or left on the bed, suitable guide strips or splines 7 engaging recesses in the

machine frame and bed to prevent displacement of the machines during such movement, and bolts 9 are carried by each machine frame and adapted to T-shaped slots 10 in the bed, serving to firmly secure each machine in position upon the latter after adjustment. 55

Each machine comprises a frame 12 carrying the necessary gearing for operating the saws and terminating at one end in a table 13 provided with one or more screw clamps 14 whereby the bar to be cut can 60 be properly secured in position at different points throughout its length, and on each frame 12 is mounted the saw carriage 15 which is under control of a feed screw engaging with a nut on the saw carriage, 65 whereby the carriage can be operated so as to move the saws from and toward the work. 70

Each saw carriage has, at each side, a bearing 17 for a saw shaft 19, the latter 75 being provided, between the bearings, with a bevel pinion 20 which meshes with a bevel wheel 21 on a shaft 22, the latter being adapted to turn in a bearing 23 on the carriage and in a bearing 24 on the frame 12, 80 and being free to move longitudinally in the latter bearing and in the hub of a worm wheel 25, which meshes with a worm 26 on the driving shaft 27 (see Fig. 3) the latter extending throughout the entire series 85 of machines and being adapted to suitable bearings on each machine, and the worms and worm wheels being free to move longitudinally upon their respective shafts but not free from driving connection therewith, 90 so that the movements of the machines from and toward each other and movement of the saw carriages upon the frames of the respective machines may be effected without interfering with the driving connection 95 between said worms and worm wheels and the respective shafts. Power to rotate the shaft 27 may be applied thereto at either one or both ends of the same, in any convenient manner. 100

Each of the saw shafts 19 has a cutting saw 55 at each end, each saw being secured to one face of a hub which is in driving connection with the shaft by means of oppositely disposed keys 56 held in place by 105 set screws 57, as shown in Fig. 7, a certain

amount of longitudinal adjustment of each saw on the shaft being thereby permitted, so as to vary the distance between the saws, or such variation being effected by reversing the hub on the shaft, or both of these means being adapted, if desired. In any case, however, the saw is relatively close to the bearing, the projection of the shaft beyond the bearing not being sufficient to permit of any deflection of the saw due to spring in said projecting portion of the shaft, whereas if both saws are mounted upon the same projecting end of the shaft the overhang of the latter will be so great that a certain amount of spring of the same will be inevitable, and the deflection of the outermost saw will not be prevented.

In order to insure the rigid guidance of the saw carriage on the main frame, the latter has, at each side, an inwardly projecting flange at the top, and there is also a central rib 50 with oppositely projecting flanges at the top, and between the flanges of the opposite side frames and those of the central rib travel a pair of guide tongues 60, retainer plates 61 being bolted to the under sides of these tongues and bearing upon the under sides of the flanges of the said end members and rib of the frame, as shown in Fig. 2, so as to confine the saw carriage vertically to the frame as closely as is compatible with its free sliding movement thereon. The inwardly projecting ribs of the said members of the frame 12 are provided with side bushings 62 adjustable by means of set screws 63 so as to compensate for side wear and prevent any lateral looseness of fit of the tongues 60.

In Fig. 3, I have shown a diagram in which eight machines are so disposed as to simultaneously form sixteen cuts at equal distances apart, but it will be evident that, owing to the provision accorded for adjusting the machines, and the saws of each machine, from and toward each other, the location of the cuts throughout the length of the bar may be varied as desired, and the bar thereby cut into pieces of dissimilar length, if such cutting is desired.

I claim:—

1. In a multiple metal-sawing machine, the combination of the bed plate, a plurality of sawing machines each having a plurality of saws, means for mounting said machines upon the bed plate so as to permit of their adjustment from and toward each other, means for securing the saws of each machine so that they may be adjusted from and toward each other, and means for transmitting power to the saws of the different machines. 50

2. In a multiple metal-sawing machine, the combination of the saw shaft, a carriage having bearings therefor, and saws having hubs mounted outside of said bearings upon the oppositely projecting ends of the saw shaft, each saw being secured to the face of its hub and said hub projecting beyond the saw to a greater extent upon one side than upon the other, whereby the distance between the saws can be varied by reversing the hub of either saw upon the shaft. 65

3. In a metal sawing machine the combination of the saw shaft, a carriage having bearings for said shaft and having a plurality of separated guide tongues projecting downwardly therefrom, and a frame having a central support for the carriage, opposite side supports therefor, and guide slots for said tongues located on opposite sides of said central support and between the same and the side supports. 75

4. In a metal sawing machine, the combination of the saw shaft, a carriage having bearings therefor, and having projecting guide tongues with retainer plates applied thereto, and a frame comprising outer members and a centrally disposed rib, the outer members having inwardly projecting guide flanges and the central rib having a projecting guide flange on each side. 80 90

In testimony whereof, I have signed my name to this specification, in the presence of two subscribing witnesses.

WM. H. LUCAS.
